UNITED STATES PATENT OFFICE

CHARLES F. BERRY, JR., OF SPRINGFIELD, MASSACHUSETTS, ASSIGNOR TO AUTO SMOCK & CLAMP CO., OF SPRINGFIELD, MASSACHUSETTS, A CORPORATION OF MASSACHUSETTS

APRON HOLDER

Application filed October 3, 1929. Serial No. 397,051.

This invention relates to an apron holder particularly useful in connection with automobile repair work. Generally speaking, it serves the same purpose as the apron holder according to Patent No. 1,672,165 of June 5, 1928; that is, the holder is to be used for temporarily and securely clamping a larger piece of paper or similar material over the back of an automobile seat in order to protect the upper 5 holstery from contact with the greasy clothes or hands of the garage mechanic while he is working in the interior of the car. However, the structure of the holder forming the subject matter of this specification differs materially from the prior structure in a way which constitutes a substantial improvement over the prior device.

The purpose of this invention is to provide an apron holder of the kind mentioned which is formed from a single piece of material such as an elastic wire, so that there is no chance for any parts to become separated or lost, which can be stripped on and off the apron-protected back of the seat solely by utilizing the elastic properties of the device, thereby rendering its application extremely simple, and inducing the mechanic to readily avail himself of its advantages, and which, furthermore, can be manufactured and sold at a 20 very low price.

In judging the merits of different devices of this kind the question of their relative usefulness should mainly be determined by the degree of readiness with which the mechanics are found to regularly employ the device. The possible bad effects, also from a hygienic point of view, of greasy substances left on the seat coverings, are seldom fully realized by the workman and, for this reason, there prevails a tendency on his side to neglect the application of such protective means, a tendency which will be the stronger the more bothersome their application is. In the development of the holder of this invention I have, therefore, made it my task to put a device on the market which will be convincing to the garage owner, not merely because of its indubitable advantages for his customers and its low price, but mainly because of 40 the ease with which he will see himself fit to

educate his employees to the habit of constantly using these facilities.

How these various ends and other advantages have been obtained will appear from the following description and the drawing 55 pertaining to it.

Fig. 1 is a side elevation of the device with the lower looped ends slightly exposed to perspective view for the sake of clearer showing;

Fig. 1a gives the correct side-elevational projective dimensions and angular relations of the right-hand loop portion;

Fig. 2 shows the device at right angles to the position in Fig. 1;

Fig. 3 illustrates the position of the holder when attached to an apron-covered automobile seat; and

Fig. 4 illustrates a modification of the invention.

Referring to Fig. 1 and Fig. 2, it will be noted that the holder is formed from a single piece of wire, preferably round steel wire with some kind of rust-protective coating. At the top of the frame there is provided a coiled portion 10 having a number of wire turns—usually from two to three, as shown in Fig. 2. On the left side, the wire coil extends in a straight portion 11 with terminal loop 15 and, on the right side, in an arcuate portion 12 which gradually goes over into a straight portion 13 with terminal loop 14. This latter straight portion 13 and the left hand straight portion 11 enclose the acute angle a (see Fig. 1a) facing the arcuate portion 12. The plane of the left-hand loop 15 is perpendicular to the plane of the turns of the coiled portion 10 and the right-hand loop 14 is arranged above loop 15 and in a parallelly inclined position thereto, forming an angle b between the two loops which may be smaller than the before mentioned angle a between the two straight portions.

The frame or holder may be machine-bent in cold condition from coil wire and, eventually, after bending be normalized. In any event, the cost of manufacture will be very low.

Fig. 3 illustrates schematically the holder in use when mounted over a seat back 20 of

comparatively large dimensions and provided with a robe rail structure 22. The apron is shown to cover with its front end 23 the entire bottom upholstery 21 and the front side 5 of the back 20 and with its rear end 24 the entire rear side of the back.

It will be noted by comparing Fig. 1 and Fig. 3 that the various portions of the holder in its open or working condition closely 10 follow the contour of the seat and leave sufficient space to bridge a protruding cross support, such as the robe rail, near the top of the rear side of the seat. This close adaptation to the outlines of the back of the seat is 15 desirable since the space in a closed automobile is already very narrow for a person working therein. A very desirable and valuable feature of this holder is the absence of all sharp edges and corners and of projecting 20 portions in which the clothes of the laborer might get caught; all portions of the holder are rounded and smooth.

When the holder is being opened in order 25 to place it on a seat the two extensions or arms—that is, front arm 11 and rear arm 12, 18, will move with respect to each other nearly as if they had a common pivotal axis in the center of the turns of the coil 10. The 30 relative angular position of the two terminal loops will, therefore, be different to a certain extent for different openings of the holder or different dimensions of the back of the seats. However, I have found that for the 35 usual thicknesses of the seat backs, due to the general yielding properties of the frame, there is always a sufficient tangency or contact obtained between the planes of the loops and the co-acting seat surfaces to prevent the formation of lasting impressions on the 40 upholstery. The angle b formed between the two terminal loops is so selected as to insure the best contact for seat dimensions most frequently met with.

In order to make the whole structure still 45 more pliant and to meet more easily also unusual seat conditions, the design of the holder may be somewhat changed as shown schematically in the modification of Fig. 4. Instead of only one coil, this construction provides 50 two coiled portions 30 and 40 spaced a suitable distance apart by an intermediate straight or curved portion 35. It is obvious that this design will have the property of ready adaptation to the form of the seat to a 55 still higher degree than the original construction because there are now, as it were, two pivotal joints.

The two end loops need not, of course, be 60 circular in shape; any loop-like formation as, for instance, a plane spiral or oval shape, would answer the same purpose—that is, to provide a more extended contact between the holder and the seat faces. Such and similar minor changes will be within the scope of 65 the invention.

It will be understood now that the advantages designated above as the object of this invention are fully incorporated in the described structures. Such advantageous features as cheapness of manufacture, close adaptation to the seat form, absence of clothes-entangling portions and separable parts, have been emphasized already. Another feature that deserves mention is the convenience with which a number of such devices may be placed on a wall bracket or the like by means of the ear formed by the turns of the coil. Apart from these obvious advantages there exist the other, less tangible, but, to my opinion, more important factors which, reasonably, must be expected to contribute materially to a more general introduction of reliable protective means in connection with car repairs. The casual loss of holders is a matter of little concern to the 75 garage owner and will not reduce his willingness to replace the holders. The extremely simple application of the device will tend to overcome a natural hesitancy or reluctance of the mechanic to avail himself of a device the importance and usefulness of which he is not always sufficiently aware of. It is, indeed, this double aspect of the situation from the garage owner's and the mechanic's viewpoint that must be taken into consideration in any structure of this kind intended to meet with wide adoption. Also, in this respect the present structure is thought to fulfill the requirements in a particularly useful way.

Claims:

1. An elastic holder for temporarily securing a protective cover over an automobile seat or the like, consisting of a single piece of elastic material which comprises a plurality of spaced-apart coiled intermediate portions, a straight extension therefrom on one side with a loop-like terminal portion to form the one clamping arm, and an arcuate extension therefrom on the other side continued in a straight portion with a loop-like terminal portion to form the other clamping arm, said arcuate extension being adapted in clamping condition to bridge protruding seat portions, said straight continuation making with the other arm an acute angle facing the arcuate extension, and said two different-arm loop-like terminal portions being so formed and positioned relative to each other that in clamping condition the planes of the loops will lie in substantially parallel contact with the co-acting seat faces.

2. An elastic holder for temporarily securing a protective cover over an automobile seat or the like, consisting of a single piece of elastic material which comprises a coiled intermediate portion, a straight extension therefrom on one side with a loop-like terminal portion to form the one clamping arm, and an arcuate extension therefrom on the other side continued in a straight portion

- with a loop-like terminal portion to form the other clamping arm, said arcuate extension being adapted in clamping condition to bridge protruding seat portions, said straight continuation making with the other arm an acute angle facing the arcuate extension, and said two different-arm loop-like terminal portions being so formed and positioned relative to each other that in clamping condition the planes of the loops will lie in substantially parallel contact with the co-acting seat faces. 5
3. An elastic holder for temporarily securing a protective cover over an automobile seat or the like, consisting of a single piece of elastic material which comprises a plurality of spaced-apart coiled intermediate portions, a straight extension therefrom on one side with a loop-like terminal portion in a plane substantially normal to the planes of the turns of the coiled portions to form the one clamping arm, and an arcuate extension therefrom on the other side continued in a straight portion with a loop-like terminal portion to form the other clamping arm, said arcuate extension being adapted in clamping condition to bridge protruding seat portions, said straight continuation making with the other arm an acute angle facing the arcuate extension, and said two different-arm loop-like terminal portions being so formed and positioned relative to each other that in clamping condition the planes of the loops will lie in substantially parallel contact with the co-acting seat faces. 10
4. An elastic holder for temporarily securing a protective cover over an automobile seat or the like, consisting of a single piece of elastic material which comprises a coiled intermediate portion, a straight extension therefrom on one side with a loop-like terminal portion in a plane substantially normal to the planes of the turns of the coiled portion to form the one clamping arm, and an arcuate extension therefrom on the other side continued in a straight portion with a loop-like terminal portion to form the other clamping arm, said arcuate extension being adapted in clamping condition to bridge protruding seat portions, said straight continuation making with the other arm an acute angle facing the arcuate extension, and said two different-arm loop-like terminal portions being so formed and positioned relative to each other that in clamping condition the planes of the loops will lie in substantially parallel contact with the co-acting seat faces. 15
5. An elastic holder for temporarily securing a protective cover over an automobile seat or the like, consisting of a single piece of elastic material which comprises a coiled intermediate portion, a straight extension therefrom on one side with a terminal circular loop in a plane normal to the plane of the turns of the coiled portion to form the one clamping arm, and an arcuate extension therefrom on the other side continued in a straight portion with a terminal circular loop to form the other clamping arm, said arcuate extension being adapted in clamping condition to bridge protruding seat portions, said straight continuation making with the other arm an acute angle facing the arcuate portion, and said two different-arm terminal loops being so positioned relative to each other that, under clamping conditions most frequently met with, the planes of the loops will lie in substantially parallel contact with the coacting seat faces. 20
